UNITED STATES PATENT OFFICE.

LYLE J. VAN DUZER, OF LOS ANGELES, CALIFORNIA.

STUD WRENCH.

Application filed August 26, 1924. Serial No. 734,248.

This invention relates to wrenches.

The general object of the invention is to provide a stud wrench which is adapted to engage a stud or other member to facilitate its removal.

One of the specific objects of the invention is to provide a wrench comprising a member having a hollow end for the reception of a part to be removed and wherein 10 the end is provided with a gripping member for engaging the article to be removed.

Another object of the invention is to provide a stud wrench including a hollow body part together with a removable and reversible gripping member provided with teeth and adapted to engage the stud to facilitate 15 its removal.

Other objects of the invention will be apparent from the following description taken 20 in connection with the accompanying drawings, wherein Fig. 1 is an elevation, partly in section, showing one embodiment of my invention; Fig. 2 is a sectional view on line 2—2, Fig. 1 with the engaging member in elevation; Fig. 3 is a view similar to Fig. 2 showing the method of operation; Fig. 4 is an end view of the gripping member; Fig. 5 is a view similar to Fig. 1 showing a modification of the invention; and Fig. 6 is a 25 top plan view of a modification.

Referring to the drawing by reference characters, I have shown a wrench embodying the features of my invention at 10.

This wrench, as indicated, comprises a 30 body portion which may be a hollow seamless tube 11. This tube is indicated as provided with apertures 14 and 15 at its upper end. A handle member 16 having end beads 17 is arranged to extend through the 35 apertures 14 and 15. The end 18 of the handle is indicated as curved so that the handle may be moved to the dotted line position shown at 19 to facilitate carrying the tool.

40 The lower end of the tube 11 is provided with opposed round apertures 20. Within these apertures I insert a gripping member 21. This gripping member 21 as shown 45 comprises a piece of steel which is cylindrical so that it can rotate in the apertures. This member 21 is suitably hardened and has teeth or serrations 22 upon its gripping face. The gripping member 21 is provided with a head 21' to prevent its accidental 50 removal in one direction from the apertures 20. A part of the wall defining each aper-

ture 20 is tangential to the inner surface of the tubular body whereby a straight line engagement is effected between the gripping member and the body. It is unnecessary to 60 remove material from the inner wall of the body 10 to do this. The serrations 22 may be inclined as shown for a purpose to be presently described. The end of the gripping member 22 is provided with an aperture 65 through which a cotter pin or other fastening member 24 extends.

In using my wrench the hollow lower end is placed over the stud or other article intended to be removed and the tube is then 70 rotated by means of the handle 16. This rotation causes a gripping action to be brought about between the inner surface of the tube 11 and the teeth or serrations 22. As a consequence, the stud 25 may be removed thus allowing the gripping member 21 to be removed and to be reversed with the other end directed through the apertures 20. This reverses the gripping action so 75 that the stud can be replaced. 80

It will be noted that the apertures 20 are shown as each in alignment one with the other but with their centers offset to one side of the center of the axis of the tube 11. 85

Referring to the modifications shown in 85 Figs. 5 and 6 it will be noted that in this case the body portion 30 is provided with a collapsible handle 31 and with a square wrench engaging portion 32 on the upper end. The stem 30 is fitted within a body 90 33 and is secured tightly therein by means of a fastening member 34. The lower end of the body 33 is recessed as at 35 to receive the article to be operated upon. The lower end of the body 33 is provided with 95 recesses to receive the gripping member 37. The gripping member 37 and its operation is similar in all respects to that of the member 21 previously described.

From the foregoing description it will be 100 apparent that I have provided an improved stud wrench which is adapted to operate quickly and easily and which can be very economically made and which is highly efficient in use. 105

Having thus described my invention, I claim:

A stud wrench comprising an elongated tubular body portion having a handle thereon, a pair of aligned round apertures 110 adjacent one end of said tubular body portion, said apertures having their axes off-

set from the axis of said tubular body portion, a substantially cylindrical gripping member having teeth thereon, said member being fitted in said apertures and rotatable therein said teeth being arranged in an inclined plane, said gripping member having a head at one end and having a removable fastening member at the other end thereof, whereby the gripping member can be re-

versed, a part of the wall defining said apertures being tangential to the inner surface of the tubular body whereby a straight line engagement is effected between the gripping member and the body without removing material from the inner wall of the body. 10 15

In testimony whereof, I hereunto affix my signature.

LYLE J. VAN DUZER.
